UNITED STATES PATENT OFFICE.

HARRY C. MILLER, OF AKRON, AND JAMES D. TEW, OF HUDSON, OHIO, ASSIGNEES TO
THE B. F. GOODRICH COMPANY, OF NEW YORK, N. Y., A CORPORATION OF NEW
YORK.

DESIGN FOR A PNEUMATIC TIRE.

Application filed December 24, 1924. Serial No. 11,789. Term of patent 14 years.

To all whom it may concern:

Be it known that we, HARRY C. MILLER, a citizen of the United States, residing at Akron, in the county of Summit and State of Ohio, and JAMES D. TEW, a citizen of the United States, residing at Hudson, in the county of Summit and State of Ohio, have invented a new, original, and ornamental Design for a Pneumatic Tire, of which the following is a specification, reference being had to the accompanying drawings, forming a part thereof.

Fig. 1 is a plan view of a pneumatic tire casing showing our design.

Fig. 2 is a cross-section on the line 2—2 of Fig. 1, omitting internal structural details.

We claim:

The ornamental design for a pneumatic tire as shown.

HARRY C. MILLER.
JAMES D. TEW.
